UNITED STATES PATENT OFFICE.

LOUIS F. BANCROFT, OF HARTFORD, CONNECTICUT.

AEROPLANE.

1,030,764.

Specification of Letters Patent. Patented June 25, 1912.

Application filed March 16, 1911. Serial No. 614,835.

To all whom it may concern:

Be it known that I, LOUIS F. BANCROFT, a citizen of the United States, and a resident of Hartford, in the county of Hartford and State of Connecticut, have invented a new and Improved Aeroplane, of which the following is a full, clear, and exact description.

My invention relates to a new and novel form of aeroplane and more particularly relates to an aeroplane having automatic stabilizing devices coacting therewith.

An object of my invention is to provide means for automatically maintaining or restoring the lateral and longitudinal balance of the aeroplane.

A further object of my invention is to provide an aeroplane having stabilizing surfaces and guiding elements which may be manually operated to convert the same into additional stabilizing elements.

With the above and other objects in view, as will more fully hereinafter appear, the present invention consists in certain novel details of construction and arrangement of parts hereinafter fully described, illustrated in the accompanying drawings, and more particularly pointed out in the appended claims.

Reference is to be had to the accompanying drawings, forming a part of this specification, in which similar characters of reference indicate corresponding parts in all the figures, and in which—

Figure 1 is a plan view showing an aeroplane equipped with a preferred embodiment of my invention; Fig. 2 is a side elevation of the same; Fig. 3 is an end elevation looking from the right hand side of Fig. 2; Fig. 4 is a perspective view of my stabilizing and supporting planes; Fig. 5 is a diagrammatic cross sectional view showing my aeroplane in tilted position; and Fig. 6 is a similar view after the aeroplane has fallen a short distance.

In the preferred embodiment of my invention herein described, I have shown a supporting framework A to which is affixed any preferred form of transverse main supporting plane B and centrally extending from the rear of which is a propeller C. Disposed in front of the transverse plane B is a vertical steering rudder D and a horizontally-disposed steering rudder E. In the preferred embodiment here disclosed I have shown an aeroplane composed of rigid

dihedrally-inclined front main sustaining wing surfaces B, parabolically curved from front to rear and elongated transversely to the line of flight, and two rigid parallel supplementary stabilizing planes 7 and 8 which are normally flat and elongated in a direction coincident with the line of flight but transversely inclined from the horizontal, this inclination being downward and inward from the outer to the inner longitudinal margins of the supplementary stabilizing planes, as more particularly shown in Figs. 3 and 4. These supplementary planes are preferably supported by an extension 9 from the framework A, which framework is extended beyond the ends 10 of the stabilizing planes, to form a rigid extension 11 for the pivoted tails hereinafter described.

To the rear margins of the stabilizing surfaces 7 and 8 and adapted to rest in a normal position on the extension 11 of the framework A are pivoted tail sections 12 and 13, forming in their normal position, a continuation, respectively, of the surfaces 7 and 8. These pivoted tail sections are so constructed that under normal conditions of flight, they extend substantially rearwardly and offer the minimum resistance to the forward motion of the machine but are adapted to automatically swing upwardly, for the purpose of preserving the longitudinal balance of the aeroplane. In devices of this character, the weights carried at different times over the front main sustaining wing surface may vary according to the weights of different operators or whether one or more passengers are being carried.

Normally the tail sections rest on the extension 11, but in order to maintain the device in its horizontal position when falling, it has been found necessary to limit the free upward swing of the tail sections 12 and 13, and for this purpose I attach flexible adjusting cords 14 and 15 to the rear under portions of the pivoted tail sections, which cords pass downwardly under the end 10 to which the tails are pivoted through pulleys 16 and 17 to an adjusting spool 18 placed convenient to the operator and which is controlled by means of a ratchet lever 19, so that by turning the spool in one direction, the adjusting cords are simultaneously tightened, thereby limiting the amount of swing of the tails 12 and 13, so that the angle of the upward swing of the pivoted tail sections from the extension 11 may be

regulated thus affording less resistance to the downward movement of the rear portion of the aeroplane due to the fact that the tail sections are more inclined to a vertical position. These tail sections having once been adjusted for any given weight in the forward portion of the machine, the spool may be locked in position, so that should the device begin to fall, the rear tails will be 5 swung through a definite and predetermined angle.

The vertical and horizontal rudders are placed in front of the machine, as shown in Fig. 1, in order to afford an unrestricted 10 channel for the current of air generated by the revolving propeller C. The horizontal rudder E is pivoted at 20 to the front framework of the machine. Extending upwardly from and rigidly affixed to the rudder is a 15 lever arm 21, to the upper end of which is pivoted one end of a horizontally-disposed arm extending rearwardly toward the operator, the rear end of which arm 22 is pivoted to the upper end of the standard 23, which 20 standard is journaled by means of a ball-and-socket connection 24 to the body of the machine. By moving the standard forward and backward, the inclination of the rudder E to the horizontal is raised or lowered as 25 desired; thus the rudder E may be inclined downward until it is in the same relative angular position with reference to the horizontal plane of the machine as the members 30 7 and 8.

In the operation, while the aeroplane is 35 moving forwardly through the air, the tail sections 12 and 13 extend rearwardly supported on the extension 11, forming substantially a continuation of the planes to which 40 they are respectively attached. Should for any reason the progress of the machine be interrupted, the device will of course begin to settle, and the resistance of the air underneath the tail sections 12 and 13 will cause 45 these sections to swing upwardly on their pivots to an angle depending upon the angle to which these planes were limited by means of the spool 18. If for any reason the machine should tilt transversely, as shown in 50 Fig. 5, it will be observed that the stabilizing planes being strongly braced and held rigidly in position with reference to each other and to the rest of the machine, are now inclined at different angular positions with 55 reference to the line of fall. Owing to the fact that the stabilizing surface 7 is inclined more toward the perpendicular and the horizontal surface 8 is inclined more to the horizontal, it will readily be seen that the right- 60 hand side of the aeroplane is retarded in its downward movement, thus allowing the portion on the surface 7 to drop downwardly and the machine to regain its normal horizontal position. It will thus be seen that whichever 65 side is tilted downwardly will present an ex-

tended retarded supporting surface on that side, which will tend to maintain the machine in a horizontal position. As the machine is dropping, the operator may manually actuate the horizontal supporting rudder E to an angle corresponding to the angle at which the stabilizing planes 7 and 8 are disposed, thereby extending the stabilizing surface across the front of the machine.

Many changes could be made in the above construction and many apparently widely different embodiments of this invention could be made without departing from the scope thereof, as, for instance, extending the stabilizing planes 7 and 8 forwardly from the plane B or even in position both forwardly and rearwardly.

It is intended that all matters contained herein, in the above description or shown in the accompanying drawings, shall be interpreted as illustrative and not in a limiting sense. It is also to be understood that the language used in the following claims is merely intended to cover all the generic and specific features of the invention herein described and all statements of the scope of the invention, which, as a matter of language, might be said to fall therebetween, and that materials, sizes and relativities of parts are non-essential, except as called for in the claims.

Having thus described my invention, I claim as new and desire to secure by Letters Patent:

1. In an aeroplane, a supporting surface, angularly-disposed stabilizing surfaces rigidly affixed to said supporting surface and extending rearwardly therefrom in the direction of the line of flight, tails pivoted to said stabilizing devices, and means limiting the angular disposition of said tails with reference to said aeroplane when the same is falling.

2. In an aeroplane, a transversely-disposed main supporting plane, and a stabilizing device disposed in the rear of said supporting plane, said stabilizing device comprising two spaced apart downwardly and inwardly inclined supporting surfaces rigidly affixed relatively to said main supporting plane.

3. In an aeroplane, a transversely-disposed main supporting plane, and a stabilizing device disposed in the rear of said supporting plane, said stabilizing device comprising two spaced apart downwardly and inwardly inclined supporting surfaces rigidly affixed relatively to said main supporting plane, the rear part of each of the planes comprising the stabilizing device adapted to swing out of the plane containing the other part of the plane comprising the stabilizing device.

4. In an aeroplane having a main supporting surface, an angularly disposed sta-

bilizing device rigidly affixed to said supporting surface and extending rearwardly therefrom in the direction of the line of flight, a framework extending to the rear of 5 said stabilizing device, a tail section pivotally attached to said framework at its front edge and adapted to normally lie on said framework, and means attached to said tail section limiting its movement away 10 from said framework.

5. In an aeroplane, a transversely-disposed main supporting surface, a stabilizing device extending from the rear of said surface and rigidly attached thereto, said stabilizing device comprising a pair of transversely spaced apart downwardly and inwardly-inclined supporting planes, a frame- 15

work supporting each of said planes and extending to the rear thereof, a supplemental tail section pivoted to said framework immediately in rear of each of said inclined planes and adapted to normally rest upon said framework, and means attached to the rear free end of each of said tail sections limiting the upward swing of 20 25 said tail sections away from said framework.

In testimony whereof I have signed my name to this specification in the presence of two subscribing witnesses.

LOUIS F. BANCROFT.
